UNITED STATES PATENT OFFICE.

McCLINTOCK YOUNG, OF FREDERICK, MARYLAND.

BRUSH-MACHINE.

SPECIFICATION forming part of Letters Patent No. 423,508, dated March 18, 1890.

Application filed May 21, 1889. Serial No. 311,572. (No model.)

To all whom it may concern:

Be it known that I, MCCLINTOCK YOUNG, of Frederick, in the county of Frederick and State of Maryland, have invented certain Improvements in Brush-Machines, of which the following is a specification.

My invention relates to a machine adapted to receive a perforated brush-block and a mass of bristles and metal fastening devices, divide the bristles into tufts, double the tufts, and drive the tufts and their fastening devices to their places in the body automatically.

Figure 1 is a front elevation of my machine with the parts in their normal positions. Fig. 2 is a side elevation of the same. Fig. 2^a is a section on line 16 16 of Fig. 2, showing the manner in which the slides are mounted one upon the other. Fig. 3 is a front elevation of the principal parts of the machine, the operating cam and lever being omitted and the parts shown in the position which they occupy in an intermediate stage of the operation. Fig. 4 is a horizontal section on the line 11 11 of Fig. 3, looking downward. Fig. 4^a is a plan view 25 showing in detail the spring-actuated eccentric to hold the brush-block in its guide. Fig. 5 is a cross-section on the line 2 2 of Fig. 3. Fig. 6 is a cross-section on the line 3 3 of Fig. 3. Figs. 7, 8, and 9 are front elevations showing the bristle separating and carrying devices in different positions. Fig. 10 is a perspective view of the devices for forming and inserting the tufts. Fig. 11 is a view, partly in section, looking downward from the line 5 5 of Figs. 35 1 and 12, showing particularly the devices for separating a layer of bristles from the mass in the reservoir. Fig. 12 is a vertical cross-section through the same on the line 6 6 of Fig. 11. Fig. 13 is a perspective view of the 40 needles employed in separating and transferring the bristles. Figs. 14 and 15 are detail views showing the successive steps in the operation of forming and inserting the tufts, the parts being viewed in side elevation. Figs. 45 16 and 17 are cross-sections through the tuft inserting and securing devices in different positions. Figs. 18 and 19 are vertical cross-sections through the bristle-carrying devices and tuft inserting and securing devices in different positions.

My machine is intended for use in the man-

ufacture of brushes which have the bristles or other fibers divided into tufts, and the tufts bent or doubled at the middle and inserted into holes in a stock or body.

Certain parts of the machine are adapted for use in forming and inserting the tufts irrespective of the manner in which they are secured in place. Other portions of the machine are particularly adapted for securing the tufts in place by means of metal fastening-strips inserted through a row of tufts and provided with teeth or projections which extend down into the holes for the purpose of keeping the tufts in place, as described and shown in my application for Letters Patent, Serial No. 287,380, filed October 6, 1888, to which reference may be made for a more detailed description of the brush.

In order that the construction and operation of my machine may be the more clearly understood, I will before describing the machine direct attention to Figs. 15 and 17, showing the construction of the brush. In these figures, X represents a brush block or body having a series of tuft-holes x bored part way therethrough in rows.

Y Y represent the tufts, formed of fibers folded or doubled at the middle and inserted at the folded ends into the holes.

Z is one of the metal fastening-strips extending transversely of the brush through the crease or bight of the row of tufts, with teeth z, which are driven down tightly into the holes, so as to bear in or against the walls of the same and also bear within the tufts to keep them in place.

The machine consists of three principal groups of mechanism—first, a table and feeding device for sustaining the previously-bored blocks and feeding them forward step by step to present the successive rows of holes in position to be filled; second, a reservoir for bristles or other fibers, combined with devices by which the fibers are removed from the mass in suitable layers or slices and the layers presented in position above the brush-block; third, mechanism by which the layer of bristles is divided into tufts, the tuft folded over and around the metallic fastening-strips, and the strips and tufts finally driven downward to their places in the brush or body.

Referring to the drawings, A represents a rigid frame, which may be of any suitable form adapted to sustain the operative parts, and mounted on legs, as shown, or otherwise sustained.

B represents the bed or table to sustain the brush-blocks, one at a time, in position to receive the tufts. It is grooved in its upper face to receive and guide the block, and provided with lips b to hold the block down in place, while allowing it to slide endwise. A spring b', fastened to one side of the table, as shown in detail in Fig. 4^a, acts on an eccentric or block b², seated in the side of the table, so as to bear on the edge of the block and hold the same snugly in place. The table stands normally in a horizontal position, so that the tufts will enter the block vertically; but in certain classes of brushes the tufts at the ends are seated in inclined holes, and to permit their insertion the table is connected to the main frame by a horizontal pivot b³, so that it may be tipped or inclined endwise. A sliding pin b⁴, mounted in the under part of the table, may be engaged in either one of a series of holes b⁵ in the frame to keep the table in position. The brush-block is advanced step by step on the table by a dog b⁶, pivoted to the upper end of a lever b⁷, pivoted in turn to the frame at its middle and having at its lower end a stud b⁸. The dog and lever are retracted by spring b⁹, but advanced by an incline b¹⁰ on the edge of cam-plate D, which acts against the stud b⁸. During its advance the dog engages directly with the brush-block, entering the holes therein and carrying it forward the required distance. During its retreat the dog slides freely over the block, after which it remains at rest. The cam-plate, which has other important functions hereinafter explained, is sustained on the main frame by a horizontal journal d, and is provided with a hand-lever d' by which it is vibrated. The lever is provided with a weight d² to counterbalance the cam-plate.

The above are all the parts necessary to sustain and advance the brush-blocks.

Passing now to the mechanism for presenting the bristles above the brush-block, attention is directed principally to Figs. 1 to 12. The bristles or fibers e, cut to a uniform length, are laid horizontally in quantity in a magazine E, in which they are fed gradually downward until delivered at the lower end. This magazine, which is fixed to the frame, is in the form of a box or channel open at the front and two ends. It stands for convenience in an inclined position, with its lower end somewhat above and to the right of the place occupied by the brush-block. The lower end of the magazine is normally closed, and the mass of bristles sustained therein, as shown in Figs. 2, 3, 7, and 12, by one end of an underlying arm f, formed on a casting F, mounted on a horizontal pivot f', so that it may be tipped to the left in order that the

arm f may be carried from under the magazine to a horizontal position over and across the brush-block, as shown in Fig. 3. The arm f is intended to receive a layer or slice of bristles and carry the same from the magazine to the position over the brush-block, where the slice is subdivided into tufts, and the latter driven down into the block. The separation of the slice or layer of bristles from the mass, and the confinement of the slice upon the arm f is secured by two blades G and H. The upper blade G is attached to a slide g, moving in a grooved guide g' on the main frame, so that when the slide is advanced the blade is thrust through and across the magazine and the mass of bristles therein parallel with the face of arm f at a distance of a quarter of an inch more or less therefrom, as shown in Fig. 8, thus separating the slice or layer between the blade and arm from the mass above. The secondary blade H is carried by a slide h, moving in a groove in arm f, as shown in Figs. 3, 4, and 5, and is arranged to fit within the main blade G, as shown in Figs. 11 and 12, so that the two blades advance as one through the mass of bristles. After they have advanced, the arm f swinging to the left carries with it the blade H, as shown in Figs. 9 and 10. The blade H acts at this time to hold the slice or separated bristles down in position on the carrier-arm f, while the blade G, remaining at rest, sustains the mass of bristles in the magazine, as shown in Fig. 9. The blade G receives its reciprocation through a roller g³ on its side extending into a suitably-shaped slot g⁴ in the cam-plate D. The blade H receives its reciprocating motion from the blade G, through a stud g⁵ on the latter engaging in a cavity h' in the former. Although these parts are disconnected when arm f swings forward, the connection is re-established when the arm f returns preparatory to the retraction of the blades. Accidental motion of the blade H is prevented by a friction-spring h³, fastened to arm f, as in Fig. 12.

The swinging motion of arm f is secured by a roller f³, on casting F, extending into a slot f⁴, in the cam-plate D. When the cam-plate is swung upward or forward by its lever d', the slot g⁴, acting on roller g³, causes the two blades to be thrust through the mass of bristles. As soon as they complete their motion, the roller g³ reaches a part of the slot which is so curved that the advance of the blades ceases.

During the above action the roller f³ receives no motion from the slot f⁴, but at the next movement said slot acts to swing the casting F and its arm f forward until the bristles carried by the arm lie above, but at a distance from, the brush-blocks, as in Figs. 3 and 10.

When the motion of the cam-plate is reversed, it first restores the arm f to its place against the mouth of the magazine, and then retracts the blades, that the mass of bristles

may descend upon the arm preparatory to the removal of the next slice.

The mass of bristles is urged downward by a follower I on the end of a rod i, which is seated in suitable guides and provided with a feeding-dog consisting of a loosely-sliding block i', containing a pivoted weighted tongue i'', which encircles the rod in such manner that it bites thereon in a familiar manner 5 when the block moves down. The sliding block is connected by link i' with a lever i⁴, pivoted to the main frame and provided at its lower end with a stud i*, arranged in the path of cam-plate D. A spring i⁵, acting on 10 the lever, urges the feed-dog upward when the parts are released, but when cam-plate D descends to return carrier-arm f to the magazine it actuates lever i⁴ and causes the follower to press the bristles down.

15 Passing now to the mechanism for dividing the slice of bristles on arm f into tufts, and seating the latter in the brush-block, attention is directed chiefly to Figs. 1, 2, 3, and 14 to 19. That the other parts may be understood, 20 it is first to be noted that the bristles lie transversely of the arm f—that is to say, in the direction of the length of the brush-block. It is also to be noted that the blade H, overlying the bristles, has a longitudinal vertical 25 slot h⁶ therein, and that the arm f contains a corresponding slot f⁶ beneath the bristles, as shown in Figs. 11, 12, and 18, to admit of the 30 bristles being driven down therethrough.

On the main frame, directly above the table, 35 is mounted a vertical slide J, to which there is firmly attached a blade j, having its lower edge provided with a groove j' to receive and retain the upper edge of the metal tuft-fastening strip z, as shown in Figs. 10 and 14, 16, 40 17, &c. A spring-finger j³ is attached to the blade to rest upon and assist in retaining the fastening-strip; but this finger may be omitted provided the strips are slightly sprung or bent to cause them to bind in the groove.

45 To the face of the slide J there is attached by suitable guides j¹⁰ (see more particularly Fig. 2^a) a second plate K, having an independent vertical motion. The lower end of this independent plate is formed with pointed 50 teeth k, designed to pass down through the slice of bristles and separate the same into tufts. A spring k' tends to force the plate K downward beyond the blade j, but a link k² connects the plate with a lever k³, pivoted 55 on the slide J, and arranged to encounter a fixed projection k⁴ on the frame, so that when the slide approaches its uppermost position the toothed plate is raised above the end of the blade, as in Figs. 2 and 3. This permits 60 the fastenings to be readily inserted in the exposed end of the blade.

When the slide is lowered, the toothed end of the plate descends beyond the blade and the teeth pass down through the blade H and 65 arm f, and the bristles held thereby, separating the bristles, as shown in Fig. 14 and in dotted lines in Fig. 10, into tufts. The de-

scent of the toothed plate continues until it acts to double or fold the tufts and carry them down through the slot in arm f, as in 70 Fig. 19, and finally comes to a rest with its teeth resting in the brush-block between the tuft-holes, as in Fig. 15. While the tufts are being doubled or folded the blade J commences its descent and carries the fastening-strip down 75 within the fold or bight of the tufts, and, continuing its descent after the plate K is at rest, it causes the fastener to carry the tufts down between the guiding-teeth into the holes in the block, where they are followed and secured by the teeth of the fastener, as shown 80 in Figs. 16 and 17.

It will be perceived that the toothed blade serves the dual purpose of separating the tufts, and of guiding them in their descent 85 after the separation, and that the plate j serves not only to present the fastener within the tufts, but to carry both the fastener and the tufts home to their places in the block.

The slide may be actuated by any suitable 90 means, but I commonly connect it by link j³ to a crank-arm on shaft j⁴, which is seated in bearings in the frame and provided with a hand-lever j⁵.

The fastening-strips may be inserted in the 95 inserting-blade j by hand, but in order that the attendant may feed them more easily to the machine I provide a guide L, grooved horizontally in its face to admit of the strips 100 being slipped therein. It is fixed to the frame in such position that its groove registers with that in the elevated blade. A slide l is 105 mounted in the guide and connected by link l² with arm f, so that when the latter swings toward the magazine it advances the slide, and vice versa.

When arm f is down, the attendant lays a fastener into the guide in advance of the slide, and when arm f swings back, the slide forces the fastener endwise to its place in the 110 blade j.

In operating the machine the brush-block is placed on the table, the magazine filled with bristles, and a fastener placed in the blade j. The hand-lever d' being then raised, 115 the cam-plate D first thrusts the blades G H through the bristles and then swings the arm f and blade H down until the bristles overlie the holes which are to receive them. The second lever j⁵ being thus actuated causes 120 plate K to descend and separate the slice into tufts and the tufts to double down through arm f. This action is followed by the descent of the blade and fastener and the driving of the fastener and tufts into the 125 block. The lever j⁵ is then returned to its first position, thereby elevating the blade and the toothed plate. A new fastener is now inserted in the guide and lever d depressed, 130 thereby restoring the arm f to the magazine, delivering the fastener to its blade, retracting the dividing-blades, and actuating both the block and bristle-feeding devices.

In order to prevent the spreading or open-

ing of the folded tufts as they pass from the slot in arm *f* to the block, the arm is provided on the under side and on opposite sides of its slot with two plates *f*⁹ and *f*¹⁰, the former fixed and the latter hinged and urged toward its companion by spring *f*¹¹.

I have described and illustrated my machine in the form which I have found best adapted for general use, but it is to be understood that the details may be modified as desired, provided the general mode of action remains the same.

As regards the bristle-separating devices, the essential features are the co-operating blades and the movable arm acting in connection with one of the blades to transfer the separated bristles from the magazine to a position opposite the brush-block, and it is manifest that the means for sustaining and moving said parts are not of the essence of the invention.

As regards the mechanism for dividing the bristles into tufts and inserting the tufts and fasteners, the essential elements are the toothed plate and the independently-moving blade combined with a slotted bristle-support. The skilled mechanic will at once perceive that their forms may be modified, and that they may be sustained and actuated by various devices, the equivalents of those herein shown.

In order that the outer end of the blade *G* may be supported and prevented from sagging under the weight of the bristles in the reservoir when the blade is in an operative position thereunder, I provide the arm *r*, which is attached to the side of the reservoir and extends outward and downward therefrom. This arm is provided near its end with an opening *r*² formed to permit the passage of the blade and is further provided below this opening with a foot *r'* in position to support the end of the blade.

I do not claim herein the combination of the toothed blade for separating the bristles into tufts with a second blade acting directly upon the tufts to force them to their seats, the same being the subject-matter of an application of even date herewith, Serial No. 311,571.

Having thus described my invention, what I claim is—

1. In a brush-machine, the grooved table to sustain the brush-block, the feed-dog overlying the table, adapted and arranged to directly engage and move the block, the dog-actuating lever, and the cam to move said lever.

2. In a brush-machine, the main frame, the block-sustaining table pivoted thereto, the lever pivoted to the frame, the block-feeding dog attached to the lever and having its active end substantially coincident with the pivot of the table, whereby the table and block may be inclined without affecting the action of the dog.

3. The magazine for bristles, in combination with the movable arm closing against its delivery end, and the two reciprocating

blades, one of which is mounted to move with the arm.

4. The magazine, the blade *G*, sustained in a fixed guide and movable through and across the magazine, the swinging arm *f*, and the reciprocating blade *H*, mounted thereon and adapted to advance with the first blade through the magazine and then separate laterally therefrom, as described.

5. As a means of separating a slice or layer of bristles from the end of a mass in a magazine, two blades adapted to be laterally joined and separated, as described, and supports, substantially as shown, permitting said blades to be moved longitudinally in unison and to be laterally separated, whereby the blades may be thrust as one through the mass and then laterally separated that one may sustain the mass while the other removes the slice therefrom.

6. In combination with the magazine, the reciprocating blade *G* and its actuating-cam, the swinging arm *f* and its reciprocating blade *H*, constructed to interlock with and receive motion from the first blade, substantially as described and shown.

7. In combination with the magazine, the follower and its rod, the feed-dog, the lever and link to actuate the rod, and the cam *D* to actuate the lever.

8. In combination with the support for the brush-block, the magazine, the intermediate vibratory arm *f* to sustain the bristles, the two blades mounted one adjacent to the magazine and the other on the arm, whereby the bristles may be presented and sustained above the block.

9. In combination with the magazine, the pivoted casting *F*, with arm *f* to receive bristles from the magazine, and the slotted pivoted cam-plate *D*, provided with an operating-lever and acting to vibrate the casting, as shown.

10. In combination with the magazine, the reciprocating blade *G*, the pivoted casting *F*, with arm *f*, the reciprocating blade *H* thereon, and the cam-plate *D*, slotted, as shown, to move the casting and the blades alternately.

11. In combination with a support for the brush-block, the overlying bristle-sustaining arm *f* and a blade *h*, both slotted vertically, and a reciprocating plate having the toothed end arranged to pass through the bristle-support, whereby the layer or slice is divided into tufts.

12. In combination with a bristle-support having a slot across which the bristles are laid in an unbroken slice or sheet, a plate having a toothed end movable through the slot, whereby the slice is divided into tufts and the tufts folded or doubled.

13. In combination with a supporting-plate having a slot across which the bristles may be laid in an unbroken slice or sheet, a plate having a toothed end to pass through the slot, and a second plate or blade grooved in its end to receive a tuft-fastener and movable

independently of the toothed plate to force the tufts and fastener into the brush-block.

14. In combination with a support for the brush-block, the slotted bristle-support overlying the same, the vertical slide provided with the grooved blade, the independently movable toothed plate mounted thereon, the spring to depress said plate, and lifting devices, substantially as shown, to elevate the plate relatively to the blade.

15. In combination with the grooved reciprocating blade J, the guide L, and its slide l, for inserting the tuft-fastening strips in the blade.

16. In combination with the grooved plate J, guide L, and slide l, the vibratory bristle-

carrying arm and the slide-operating link connected thereto, whereby the bristle-carrying arm is enabled to present the bristle-fastening strip to the inserting-blade.

17. In combination with the slotted bristle-sustaining arm f and the blades movable therethrough, the fixed plate f⁹, and the hinged spring-actuated plate f¹⁰.

In testimony whereof I hereunto set my hand, this 8th day of May, 1889, in the presence of two attesting witnesses.

McCLINTOCK YOUNG.
